(57) **CLAIM**

The ornamental design for a display screen or portion thereof with graphical user interface, substantially as shown and described.

DESCRIPTION

The file of this patent contains at least one drawing/photograph executed in color. Copies of this patent with color drawing(s)/photograph(s) will be provided by the Office upon request.

FIG. 1 is a front view of a display screen or portion thereof with graphical user interface, showing a first embodiment of the new design;

FIG. 2 is a second embodiment thereof;

FIG. 3 is a third embodiment thereof;

FIG. 4 is a fourth embodiment thereof;

FIG. 5 is a fifth embodiment thereof;

FIG. 6 is a sixth embodiment thereof;

FIG. 7 is a seventh embodiment thereof;

FIG. 8 is an eighth embodiment thereof;

FIG. 9 is a ninth embodiment thereof;

FIG. 10 is a tenth embodiment thereof;

FIG. 11 is an eleventh embodiment thereof;

FIG. 12 is a twelfth embodiment thereof;

FIG. 13 is a thirteenth embodiment thereof;

FIG. 14 is a fourteenth embodiment thereof;

FIG. 15 is a fifteenth embodiment thereof;

FIG. 16 is a sixteenth embodiment thereof; and,

FIG. 17 is a seventeenth embodiment thereof.

The broken lines in the figures show a display screen or portion thereof, and form no part of the claimed design.

The term "FLEXFIT" forming part of the claimed design is a trademark of Sleep Number Corporation.
